HENRY G. VOIGHT, OF NEW BRITAIN, CONNECTICUT, ASSIGNEE TO SARGENT & COMPANY, OF NEW HAVEN, CONNECTICUT, A CORPORATION OF CONNECTICUT.

LOCK.

1,152,457.

Specification of Letters Patent.

Patented Sept. 7, 1915.

Application filed June 4, 1915. Serial No. 32,109.

To all whom it may concern:

Be it known that I, HENRY G. VOIGHT, of the town of New Britain, county of Hartford, and State of Connecticut, have invented certain new and useful Improvements in Locks, of which the following is a full, clear, and exact description.

This invention relates to locks which are furnished with means for indicating whether the door is locked or unlocked, and it refers more especially to a lock for hotel corridor doors having an indicator which can be read by feeling or touch as well as visually.

15 The indicating mechanism of my invention is particularly well adapted to indicate at a point on the outside escutcheon, the position of the outside bolt in a two-bolt lock of the general type illustrated in Letters 20 Patent No. 898,434, granted to Sargent & Company, on September 15, 1908, as assignee of William J. Carroll. Nevertheless, certain features of my improvements may be used to advantage in other applications or connections.

30 The primary object of the invention is to provide simple, effective mechanism for translating the movements of the bolt into corresponding movements, in a direction depth-wise of the door, of an indicating member or plunger associated with the outside escutcheon.

To this and other ends, the invention consists in the novel features and combinations 35 of parts to be hereinafter described and claimed.

In the accompanying drawing, Figure 1 is a fragmentary outside elevation of a door equipped with an indicator lock embodying 40 my invention, showing the bolt in its retracted position; Fig. 2 is a similar view, showing the bolt in its protracted position; Fig. 3 is a section on line 3—3 of Fig. 1, looking to the right; Fig. 4 is a section on line 4—4 of Fig. 2, looking to the left; and Fig. 5 is a rear face view of that portion of the escutcheon which carries the indicator.

Referring to the drawing, the door 10 is shown equipped with a mortise lock 11 having a dead bolt 12. This lock is not shown in detail, but the bolt 12 may be the outside bolt of a two-bolt lock constructed in accordance with Patent No. 898,434 mentioned above. The outside escutcheon 13 is provided with a keyhole 14 for the insertion

into the keyhole 15 of the lock case of a key adapted to operate the bolt 12 in the usual manner. Mounted on the outside escutcheon 13 at a point adjacent the bolt 12 is a bushing or housing 16 which may be constituted by a sleeve appropriately secured to the escutcheon at the inner face of the latter. The bushing or sleeve is provided with a large bore 17 at the rear part adapted to receive the body portion 18 of an indicating member 60 or plunger 19, the forward end of which is of somewhat reduced diameter, and fits a smaller bore 20 communicating with the bore 17. The junction of the body portion 18 of the plunger with the reduced head portion 65 forms a shoulder adapted to limit the forward movement of the plunger relative to the escutcheon, as will be understood. A pin 21 driven into the side wall of the bore 17 fits an inclined groove 22 in the body portion 70 of the plunger in such a manner that as the plunger is turned on its axis it will be advanced or retracted in the bushing. Thus the plunger has a screw movement in the escutcheon.

75 The turning movement of the plunger is imparted to the same by means of a sliding member 23. This sliding member is preferably in the form of a plate carried by the bushing, and in the present instance it is 80 slidably secured to the bushing by means of small screws 24 passing through longitudinal slots 25 in the plate, and into threaded holes in the rim of the bushing, as shown in Fig. 5. Between the slots 25, the plate 23 is provided with a small transverse notch 26 engaging a pin 27 extending from the rear face of the plunger and eccentrically mounted on the plunger. By this means, the plunger is turned on its axis, and thereby 85 advanced or retracted, as the slide 23 is moved in one or the other direction on the bushing. The slide is operated in a suitable manner from the bolt 12, and in the form shown, the tumbler stump 28 on the 90 bolt carries a pin 29 which extends through a clearance slot 30 in the lock case and engages a transverse notch 31 in the plunger 95 actuating slide.

100 The operation of the device will be obvious for the most part from the foregoing description. In the particular form shown, the plunger is retracted from the escutcheon when the bolt is in the retracted position. Thus a chamber-maid or any one familiar 105

with the general working of the indicator will know that the bolt is retracted as soon as it is determined that the plunger is retracted which can be done either visually or by running the finger over the end of the bushing. As the bolt is protracted by the key, the pin 29 will move with the bolt in a straight line, and will shift the slide 23 in such a direction as to move the plunger out in the bushing until its end face is substantially flush with the outer face of the escutcheon. Then the filling up of the end of the bushing, or of the depression in the escutcheon, will indicate that the bolt is in the protracted position. When the corridor is dark or poorly lighted, the chamber-maid may readily determine the position of the plunger by feeling the escutcheon, or, to be more exact, by placing her thumb or finger over the mouth of the plunger guide, which is open in one position of the bolt and filled up in the other position. I do not limit myself to a construction in which the substantially flush position of the plunger relative to the escutcheon corresponds to the protracted position of the bolt, as an obvious reversal of this arrangement would be within the scope of my invention.

Without limiting myself to the precise construction shown, I claim:—

1. The combination with a lock having a bolt, of an escutcheon, a housing or bushing on said escutcheon, a plunger having a screw movement in said housing or bushing, a

slide to operate said plunger, and a projection on the bolt to operate the slide; substantially as described. 35

2. In an indicator lock, the combination of an escutcheon, a plunger having a screw movement in the escutcheon, and a slide 40 mounted on the rear face of the escutcheon and adapted to actuate said plunger; substantially as described.

3. The combination with a lock having a bolt, of an escutcheon, a housing or bushing 45 mounted on said escutcheon, a plunger having a screw movement in said housing or bushing, a sliding member carried by the housing or bushing and movable laterally thereon to actuate said plunger, and means 50 of connection between said sliding member and said bolt; substantially as described.

4. In an indicator lock, the combination of an escutcheon, a bushing thereon, a plunger having a screw movement in the bushing, an actuating plate, means mounting said plate for lateral sliding movement on the rear end of the bushing, and an eccentric pin on the plunger engaging a notch in said plate; substantially as described. 55

5. In an indicator lock, the combination of an escutcheon, a plunger having a screw movement in said escutcheon, and a laterally shiftable actuating slide for the plunger; substantially as described. 60

In witness whereof, I have hereunto set my hand on the 2nd day of June, 1915.

HENRY G. VOIGHT. 65
